UNITED STATES PATENT OFFICE.

ROBERT C. McCaleb, OF CHICAGO, ILLINOIS.

CENTRIFUGAL WASHING AND DRYING MACHINE.

1,253,403.

Specification of Letters Patent. Patented Jan. 15, 1918.

Application filed April 3, 1917. Serial No. 159,456.

To all whom it may concern:

Be it known that I, ROBERT C. McCaleb, a citizen of the United States, residing at Chicago, in the county of Cook and State of Illinois, have invented a new and useful Centrifugal Washing and Drying Machine, of which the following is a specification.

The present invention relates to a centrifugal washing and drying machine, and aims 10 to provide a novel and improved appliance of that character for washing clothes and drying them, or for doing other similar work.

One of the objects of the invention is the 15 provision of a device of that character, the tub and corresponding parts of which can be tilted from horizontal to vertical position.

Another object of the invention is the 20 provision in a machine of the character specified, of means for dipping the water or cleaning fluid from the lower portion of the tub and raising it up and throwing it from the center outwardly into the rotatable 25 basket by centrifugal force.

A further object of the invention is the provision of a novel driving gearing for the basket, whereby the basket can be rotated at a relatively high speed when in horizontal 30 position, and at a relatively low speed when in a vertical position.

With the foregoing and other objects in view which will appear as the description 35 proceeds, the invention resides in the combination and arrangement of parts and in the details of construction hereinafter described and claimed, it being understood that changes in the precise embodiment of the invention herein disclosed, can be made 40 within the scope of what is claimed, without departing from the spirit of the invention.

The invention is illustrated in the accompanying drawing, wherein:—

Figure 1 is a vertical median section of 45 the machine, portions being shown in elevation.

Fig. 2 is a fragmental elevation.

Fig. 3 is another fragmental elevation showing the tub tilted to vertical position.

50 In carrying out the invention, there is provided a tub 1 of any suitable construction, having the top 2 provided with the hinged section or door 3 permitting access to the interior of the tub. The bottom or 55 side portion of the tub is trunnioned or piv-

oted to a pair of legs 4, whereby the tub can be swung to horizontal and vertical position. By the horizontal position is meant that the tub has its bottom in a horizontal position, and when the tub is in its vertical position, 60 the bottom thereof is vertical. A third leg 5 is attached to the tub to swing onto and rest against the floor when the tub is in horizontal position, and said leg 5 can be engaged by a catch 6 mounted upon the 65 floor to hold the tub in horizontal position. When the catch 6 is released from the leg 5, the tub can be swung to vertical position against or adjacent to the legs 4, as seen in Fig. 3. 70

A bearing 7 is provided at the center of the bottom of the tub, and a shaft 8 is journaled through said bearing axially of the tub. A basket 9 having apertured walls has its bottom secured upon the shaft in any 75 suitable manner, and the basket has a top or cover 10 provided with the hinged section or door 11 permitting the articles to be readily placed within and removed from the basket when the doors 3 and 11 are opened. 80 Said doors can be held closed by any suitable latches or the like (not shown).

In order to dip and raise water within the tub, a plurality of rods 12 are slidable through the top 10 of the basket and are 85 provided at their lower ends with scoops or buckets 13 of suitable construction, movable downwardly through openings 14 in the bottom of the basket to the bottom of the tub. A yoke 15 connects the upper ends 90 of the rods 12 above the top of the basket and underneath the top of the tub, and a stem 16 swiveled to the yoke 15 extends slidably upward through the top of the tub to be conveniently raised and lowered by 95 hand. When the stem 16 is lowered, this will lower the scoops or buckets 13 through the openings 14 so that they will, in whirling with the basket, scoop up the water or cleaning fluid, which is in the lower portion 100 of the tub, lift it and throw it outward toward the side walls of the basket by centrifugal force to pass through the clothes or other articles for washing them, the scoops or buckets being raised and lowered 105 at suitable intervals, and rotating with the basket.

Vertical bars 17 are preferably secured to the interior of the side walls of the basket, for agitating the water, and assisting in the 110

cleaning action when the basket is rotated, it being noted that when the basket is rotated, this will throw the water outwardly by centrifugal force, whereby to wash the clothes and dry them. The water is drained out of the tub through a draw off cock 18 attached to the tub at that portion thereof which swings downwardly, whereby the water can be drained out in either position 10 of the tub.

The driving gearing embodies a worm wheel 19 secured to the shaft 8 underneath the bearing 7 and a spur gear 20 secured to the shaft underneath the worm wheel 19. An 15 electric motor 21 or other suitable driving means can be used, and as illustrated, the same is carried by a bracket 22 having a bearing sleeve 23 mounted for rotation upon one leg 4. The upwardly projecting armature shaft 24 of the motor 21 has secured thereto a spur gear 25 to mesh with the spur gear 20 when the tub is in horizontal position and when the motor is swung to bring the gear 25 into mesh with the gear 20. A 20 worm 26 is carried by the shaft 24 to mesh with the worm wheel 19. Thus, when the tub is tilted to vertical position, the motor 21 can be swung with the bracket 22 to bring the worm 26 into mesh with the worm wheel 19. Thus, the shaft 8 being actuated by the 25 worm 26 and the worm wheel 19, will cause the basket to be rotated at a slower velocity than when the basket is in horizontal position with the spur gears in mesh.

30 The tub and basket can be moved to either horizontal or vertical position, according to the circumstances and the work to be done, thereby providing a convenient and desirable arrangement.

35 Having thus described the invention, what is claimed as new is:—

1. A centrifugal machine embodying a tub, a rotatable basket therein, and means movable through the bottom of the basket.

for raising water from the lower portion of 45 the tub into the basket.

2. A centrifugal machine embodying a tub, a rotatable basket therein, and a vertically movable member slidably engaging the basket and having a bucket for raising water 50 from the lower portion of the tub into the basket.

3. A centrifugal machine embodying a tub, a rotatable basket therein having an opening in its bottom, a vertically movable 55 member slidably engaging the basket and having a bucket movable through said opening upwardly and downwardly, and means for raising and lowering said member.

4. A centrifugal machine embodying a 60 tub mounted for tilting movement, a shaft carried by the tub, a basket carried by the shaft within the tub, a worm wheel and a spur gear carried by said shaft, and actuating means having a spur gear to mesh with 65 the aforesaid spur gear when the tub is in one position and having a worm to mesh with the worm wheel when the tub is in another position.

5. A centrifugal machine embodying a 70 basket and shaft therefor mounted for tilting movement, actuating means, said shaft and actuating means having gears adapted to mesh in one position of the basket to provide a certain speed and adapted to mesh in 75 another position of the basket to provide a different speed, and means for movably mounting the actuating means in order that it can be brought into connection with the shaft according to the position of the basket. 80

In testimony that I claim the foregoing as my own, I have hereto affixed my signature in the presence of two witnesses.

ROBERT C. McCALEB.
